HIRAM O. WILLIAMS, OF FEEDING HILLS, MASSACHUSETTS.

TOBACCO-PIPE.

1,058,232.

Specification of Letters Patent.

Patented Apr. 8, 1913.

Application filed November 8, 1910, Serial No. 591,323. Renewed August 29, 1912. Serial No. 717,790.

To all whom it may concern:

Be it known that I, SELIM W. GUNN, a citizen of the United States, and a resident of Feeding Hills, in the county of Hampden and State of Massachusetts, have invented certain new and useful Improvements in Tobacco-Pipes, of which the following is a specification, reference being had to the accompanying drawings.

10 This invention relates to improvements in tobacco pipes. The primary object of my invention is to provide a tobacco pipe, the bowl of which is in communication with a magazine.

15 Another object is to provide a tobacco pipe so constructed that the tobacco may be fed from the magazine into the bowl from below.

20 A further object is to provide a tobacco pipe with a magazine, a removable shield, a drain plug, and means so that the tobacco may be fed from the magazine into the bowl.

25 With these and other objects in view, the present invention consists in the combination and arrangement of parts as will be hereinafter more fully described and particularly pointed out in the appended claims, it being understood that changes in the specific structure shown and described may be made within the scope of the claims, without departing from the spirit of the invention.

30 In the drawings forming a part of this specification, and in which like numerals of reference indicate similar parts in the several views:—Figure 1, shows a side elevational view of a magazine pipe constructed according to my invention. Fig. 2, shows a central sectional view of the pipe. Fig. 3, shows a bottom view of the pipe with the magazine open. Fig. 4, shows a detached detail of the plunger. Fig. 5, is a section on line 5 of Fig. 2. Fig. 6, is a detail of the shield.

45 The aim of my invention is to provide a tobacco pipe, especially adapted to be used by soldiers, sportsmen and others, so constructed that the pipe while lighted can be charged with a fresh supply of tobacco from a connected magazine, the tobacco entering the pipe bowl from below.

50 In the accompanying drawings the numeral, 1, designates the mouth piece to the stem, and 3, the bowl of a tobacco pipe embodying my invention. As shown, the pipe

is provided with a magazine, 4, positioned below the stem, 2, this magazine by means of a discharge opening, 9, communicating with the bottom of the pipe bowl.

As clearly shown in Fig. 2, the pipe stem 60 is provided with a smoke duct, which is continued upwardly, as shown at 5, and then laterally, as disclosed at, 6, so that the draft opening communicating with the pipe stem enters the pipe bowl 3, approximately 65 midway at the bowl. The bowl is provided with a seat, 26, within which is removably held the shield, 7, said shield having the draft aperture, 8, registering with the draft opening 6. The bottom, 25, of the 70 bowl drains toward an opening, 10, leading into a cup, 11, closed by means of the screw, 12, this cup, 11, being arranged to receive the nicotine that may drain into the pipe bowl. The magazine, 4, at one end supports the screw, 13, this screw in turn pivotally holding the cap plate, 16, which covers the magazine, 4; the end of this cap plate is offset as shown at 27. To form a locking union with the shoulder, 29, of the magazine 80 shown in Fig. 2, this cap plate is further provided with an inwardly directed bead, 20, arranged to work over the edge of the magazine 4, so that the cap plate, 16, can only be opened after the bead, 20, has been 85 forced from below the magazine edge. By this means the cap plate cannot become casually or accidentally displaced. Communicating with the magazine, 4, is a slot, 15, through which extends the finger piece, 23, 90 projecting from the plunger, 22, arranged to reciprocate within the magazine. The operation of a pipe constructed according to my invention is very simple. In the use of a pipe the operator would first shove the 95 plunger 22, into its farthest rearward position, and then charge the magazine, securely closing the cap plate. The bowl of the pipe would then be charged with tobacco and the smoking operation would then be begun. 100 After the tobacco has been consumed to a point opposite the aperture, 8, in order to continue the smoking operation, the smoker would raise the shield, 7, to cover the escape opening, 9. The plunger, 22, would then be 105 forced forward, so that a part of the tobacco within the magazine, 4, would be forced into the pipe bowl, the level of the tobacco then, of course, being raised within the bowl of the pipe.

- In pipes as ordinarily constructed, the tobacco at the extreme bottom of the bowl is usually moist, and the smoker seldom consumes the same. In my invention, however, but half of the tobacco within the bowl can be consumed without requiring that the pipe bowl be re-charged. By means of the under-feed the slightly moist tobacco is carried upward to be consumed, while a fresh supply is introduced into the bottom of the pipe bowl. This is a great thing, in that the tobacco as well as the pipe is kept "sweet." As shown in Fig. 2, the bottom, 25, of the pipe bowl turns toward the opening, 10.
- 15 It is, of course, understood that pipes embodying my invention may be made in various sizes, and of various materials, and that the magazine, 4, may be given any desired capacity within certain limits.
- 20 A pipe constructed according to my invention is comparatively inexpensive, and both durable and efficient in operation, and the plunger and shield may be easily operated, while the magazine can be readily re-charged.
- 25 Having thus described my said invention, what I claim as new and desire to secure by United States Letters Patent, is:
1. In a tobacco pipe, the combination of 30 a bowl, a stem formed with a smoke duct communicating with the bowl at an intermediate point between the top and bottom thereof, a magazine arranged under the stem and communicating with the bottom 35 of the bowl, a shield normally shutting off communication between the magazine and the bowl, and a plunger within the magazine for forcing tobacco from the magazine into the bottom of the bowl, the tobacco 40 previously in the bottom of the bowl being thereby moved upwardly above the smoke
- duct of the stem so as to be consumed in the usual manner.
2. A tobacco pipe including a bowl, a stem formed with a smoke duct communicating with the bowl at an intermediate point between the top and bottom thereof, a magazine arranged under the stem and communicating with the bottom of the bowl, the said magazine having a slot in one side 45 thereof, a movable closure for one side of the magazine, a plunger mounted within the magazine, and a finger piece carried by the plunger and projecting through the before mentioned slot, the said plunger enabling tobacco within the magazine to be forced into the bottom of the bowl, thereby moving that tobacco which was previously in the bottom of the bowl upwardly above the smoke duct of the stem so that it will 50 be consumed in the usual manner.
3. As a new article of manufacture a pipe including a stem and connected bowl, said stem entering said bowl a suitable distance above the bottom thereof, said bowl being in 55 communication with a magazine and provided with a seat, a shield removable within said seat, closing the escape opening between said magazine and bowl, said magazine having an offset shoulder, a cap plate 70 covering said magazine arranged to lock with said offset shoulder, said magazine having a slot, and a plunger within said magazine having a finger piece extending through said slot, all arranged substantially as and 75 for the purpose set forth.
- In testimony whereof I affix my signature in presence of two witnesses.
- SELIM W. GUNN.
- Witnesses:
- GUIDON W. GORDON,
HIRAM O. WILLIAMS.
